ORE CONCENTRATOR

Filed Dec. 19, 1941

3 Sheets-Sheet 3

Technical drawing of a mechanical assembly labeled Fig. 4. The drawing shows a cross-section of a cylindrical component with various internal and external parts labeled with numbers 16, 20, 21, 22, 23, 28, 29, 30, 31, 32, 36, and 37. The assembly appears to be a valve or a similar control mechanism.

ORE CONCENTRATOR

Phillip H. Behrens, Kearney, Nebr., assignor of
one-third to C. A. Wilcox, and one-third to
Gilbert Phillips, both of Kearney, Nebr.

Application December 19, 1941, Serial No. 423,666

3 Claims. (Cl. 209—482)

This invention relates to an ore concentrator especially adapted for separating heavy material from light material and collectively retaining the heavy material therein and discharging the light material therefrom without the use of separating liquids, grading elements or units or the use of centrifugal force.

The primary object of this invention is the provision of a device of the above stated character, wherein heavy material will be concentrated and separated from light material by centripetal force developed by said device and which force acts to form the material mass into a vortex, the heavy material being moved toward the center of the vortex while the light material is moved outwardly of the vortex by the inward movement of the heavy material and thereby bring about the retention of the heavy material in the device and the discharge of the light material from said device.

With these and other objects in view as will become more apparent as the description proceeds, the invention consists in certain novel features of construction, combination and arrangement of parts which will be hereinafter more fully described and claimed.

For a complete understanding of my invention, reference is to be had to the following description and accompanying drawings, in which

Figure 1 is a side elevation, partly in section, illustrating an ore concentrator constructed in accordance with my invention.

Figure 2 is a front elevation illustrating the device.

Figure 3 is a sectional view taken on the line 3—3 of Figure 1.

Figure 4 is a sectional view taken on the line 4—4 of Figure 3.

Figure 5 is a detail sectional view illustrating one of the supporting rollers for the bowl of the device and its mounting.

Referring in detail to the drawings, the numeral 5 indicates a supporting structure including a horizontal portion 6 adapted to rest upon the ground or other supporting surface and to which are secured vertically arranged spaced rear members 7 and spaced front members 8 tied to the rear members 7 by braces 9 and hopper supporting members 10. The front members 8 incline upwardly in the direction of the rear members 7 and are secured to the hopper supporting members 10 and are further supported by braces 11 extending from the upper ends of the front members 8 to the horizontal portion 6 of the supporting structure. The braces 11 and front

members 8 terminate short of the rear members 7 and as the hopper supporting members 10 are carried by the front and rear members 8 and 7 said members 10 are disposed at an inclination for supporting a hopper 12 in the form of an elongated pan provided with upstanding solid walls and a solid bottom wall provided with a discharge opening 14 adjacent the lowermost end of the pan. Said lowermost end of the pan may be shaped as shown in Figure 2 to present converging upstanding wall portions leading to the discharge opening 14 so as to readily direct materials placed in the hopper through the discharge opening by gravitation.

Connected to the hopper and underlying the discharge opening is a discharge pipe 15 for directing the materials into a bowl 16.

Hinged to the upper end of the hopper and overlying the latter is a grating 17 through which materials may be graded and enter the hopper while undesirable materials may slide therefrom. If desired, the grating 17 may be swung upwardly, as shown in dotted lines in Figure 1, to give access to the interior of the hopper.

Opposed journals 18 are mounted on the braces 9 of the supporting structure between the front and rear members 8 and 7 and rotatably support a shaft 19 provided with an offset 20 directed downwardly with respect to the plane of the shaft. A housing 21 forms a part of the shaft and rotatably supports a driven shaft 22 on which is secured a worm 23 and a belt pulley 24, the latter operating within the offset 20 or the latter giving clearance for the operation of the pulley and an endless belt 25 trained thereover. The belt 25 is trained over a pulley 26 of a power medium 27 mounted on the horizontal portion 6 of the supporting structure.

The housing 21 also rotatably supports a shaft 28 forming an integral part of an attaching plate 29 bolted to the bowl 16, as shown at 30. A worm gear 31 operating within the housing 21, is secured to the shaft 28 and meshes with the worm 23.

It will be apparent from the foregoing description and the showing made in the drawings how the bowl is rotated by the power source 27.

Arms 32 are secured to the shaft 19 and extend in the direction of the front members 8 and are connected by a yoke 33 preferably of channel iron construction, as shown in Figure 5. The yoke 33 includes a connecting portion 34 and diverging portions 35 which join the arms 32. The portions 34 and 35 have adjustably mounted thereon rollers 36 for rotatably supporting the
